UNITED STATES PATENT OFFICE.

LLOYD V. LEWIS OF EDGEWOOD, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY BRAKING APPARATUS.

Application filed December 15, 1925. Serial No. 75,541.

My invention relates to railway braking apparatus, and particularly to apparatus of the type comprising a braking bar located in the trackway and a motor device for moving such bar into engagement with a part of a railway vehicle. More particularly my invention relates to means for controlling such motor device.

I will describe one form of railway braking apparatus embodying my invention, and will then point out the novel features thereof in claims.

The accompanying drawing is a view partly diagrammatic, illustrating one form 15 of railway braking apparatus embodying my invention.

Referring to the drawing, the reference characters 1 and 1^a designate the track rails of a stretch of railway track. Located on 20 opposite sides of rail 1 and extending parallel therewith are two braking bars 2 and 3. Similar braking bars 2^a and 3^a extend parallel with rail 1^a on opposite sides thereof.

The braking bars 2, 3, 2^a and 3^a are operated by a fluid pressure motor designated in general by the reference character M. This motor comprises a cylinder 5 containing a reciprocable piston 6 to which is attached a piston rod 6^a. The braking bars 2, 3, 2^a and 3^a are operatively connected with the piston rod 6^a of motor M through suitable linkage including a lever 4 pivoted at point 4^a. When piston 6 moves to its left-hand position, bars 3 and 3^a are moved to the left and 35 bars 2 and 2^a are moved to the right and the bars then occupy their non-braking positions as shown in the drawing. When piston 6 is moved to its right-hand position the braking bars are moved inwardly toward the associated rail to their braking positions in 40 which they engage the sides of the wheels of a railway vehicle traversing rails 1 and 1^a.

The motor M is controlled by three magnet valves D, E and F. Valve F comprises 45 a plunger 7 provided with an armature 7^a and a winding 8. When winding 8 is de-energized, plunger 7 rises, and the right-hand end of cylinder 5 is then connected with atmosphere through pipe 11 and port 50 10. When winding 8 is energized, however, plunger 7 is moved downwardly, disconnecting pipe 11 from port 10, and connecting this pipe, through port 9, with a suitable source of fluid pressure not shown in the

drawing. When winding 8 of valve F is energized, therefore, the fluid pressure supplied to the right-hand end of cylinder 5 moves piston 6 to the left, thereby moving the braking bars 2, 3, 2^a and 3^a away from their braking positions. 55

Valve E is somewhat similar to Valve F. When winding 8 of this valve is de-energized plunger 7 rises, thereby connecting the left-hand end of cylinder 5 with atmosphere through pipe 12 and port 13. When winding 8 of valve E is energized, however, plunger 7 is moved downwardly to blank pipe 12. 60

Referring now to valve D, when winding 8 of this valve is de-energized, plunger 7 is moved upwardly to blank pipe 12. When winding 8 of valve D is energized, however, the plunger 7 is moved downwardly, thereby connecting pipe 12, through port 14, with a source of fluid pressure not shown in the drawing. It will be plain therefore that when valve E is closed and valve D is open, fluid pressure is supplied through pipe 12 to the left-hand end of cylinder 5. Piston 6 is then moved to the right, thereby moving the braking bars to their braking positions. When valve D is closed, and valve E is open, however, the left-hand end of cylinder 5 is connected with atmosphere. 70 75 80

It is obvious that the braking force exerted upon a vehicle by the braking bars depends upon the force with which the piston 6 is moved to the right. One feature of my present invention is the provision of means for adjusting the pressure exerted upon the piston 6 and for automatically controlling such pressure. I will now describe the apparatus by means of which I accomplish this result. 85 90

The valves D, E and F are controlled in part by a plurality of pressure responsive circuit controllers. These circuit controllers are arranged in two series, the circuit controllers of one series being designated by the reference characters K and those of the other 100 by the reference characters L. Each of the circuit controllers K comprises a Bourdon tube 15, connected through pipe 17^a with the left hand end of cylinder 5. Associated with each such Bourdon tube and controlled thereby is a normally closed contact 16 arranged to be opened when the pressure in the left hand end of cylinder 5 exceeds a prede- 105

terminated value. Circuit controllers L are similar to circuit controllers K and each comprises a Bourdon tube 15 connected with a pipe 17^b which communicates with the left hand end of cylinder 5. The circuit controllers K and L are so adjusted that for pressures in cylinder 5 below a low value, such as 20 pounds per square inch, all the circuit controllers are closed. As the pressure increases above this low value the circuit controllers of each series successively open.

In the drawing the exponent for each circuit controller designates, in pounds per square inch, the pressure required to open this circuit controller. For example, K²⁰ is arranged to open when the pressure in the left-hand end of cylinder 5 exceeds 20 pounds per square inch, circuit controller K⁴⁰ is arranged to open when this pressure exceeds 40 pounds per square inch, circuit controller L²⁵ when the pressure exceeds 25 pounds per square inch, etc. It should be particularly pointed out that with each circuit controller K there is associated a corresponding circuit controller L which opens when the pressure rises a small amount above the pressure necessary to operate such circuit controller K.

The reference character G designates a manually operable selector comprising a lever 18 movable into engagement with any one of an outer row of fixed contacts 22, 24, 26, 28 and 30. The selector also comprises an inner row of fixed contacts 21, 23, 25, 27 and 29. The parts are so arranged that when the lever 18 is moved into engagement with one of the contacts in the outer row, such as contact 22, the lever also engages a corresponding contact of the inner row, such as contact 21. The selector also comprises still another fixed contact 19 so located that lever 18 may at times engage this contact.

Contact 22 is connected with one terminal of winding 8 of valve D through circuit controller K²⁰. Contact 24 is connected with this terminal through circuit controller K⁴⁰. In similar manner contacts 26 and 28 are connected with the same terminal of winding 8 of valve D through circuit controllers K⁶⁰ and K⁸⁰, respectively. Contact 30 is connected directly with this terminal. Contact 21 is connected, through circuit controller L²⁵, with one terminal of winding 8 of valve E. Similarly, contacts 23, 25 and 27 are connected, through circuit controllers L⁴⁵, L⁶⁵, and L⁸⁵, respectively, with the same terminal of this winding. Contact 29 is connected directly with the same terminal of winding 8 of valve E.

In explaining the operation of the apparatus as a whole I will first assume that the operator wishes to make a slight brake application. He accomplishes this by moving lever 18 into engagement with contacts 21

and 22. Current then flows from terminal B of a suitable source of energy, not shown in the drawing, through lever 18, contact 21, circuit controller L²⁵, and winding 8 of valve E to terminal C of the same source. Valve E is therefore closed, blanking pipe 12. At the same time current flows from lever 18, through contact 22, circuit controller K²⁰, and winding 8 of valve D, to terminal C. Valve D is therefore open and fluid pressure is admitted to the left-hand end of cylinder 5 through pipe 12. This pressure drives piston 6 to the right and moves the brake bars into their braking position. When the pressure in the left-hand end of cylinder 5 reaches 20 pounds per square inch circuit controller K²⁰ opens, thereby closing valve D and preventing further admission of fluid pressure to the cylinder. If the pressure in cylinder 5 becomes reduced, as by leakage, circuit controller K²⁰ again closes to admit fluid pressure to the cylinder. If the pressure in the cylinder for any reason exceeds 25 pounds per square inch, circuit controller L²⁵ opens and interrupts the circuit for valve E. Pressure is then exhausted from the cylinder until the pressure is reduced to 25 pounds per square inch, whereupon the circuit controller L²⁵ again closes to complete the circuit for valve E. It will be apparent therefore that when lever 18 of selector G engages contacts 21 and 22, the pressure in the left-hand end of cylinder 5 will be maintained between 20 and 25 pounds per square inch. Similarly, if lever 18 is moved into engagement with contacts 23 and 24, the pressure in cylinder 5 is maintained between 40 and 45 pounds per square inch, if lever 18 engages contacts 25 and 26, the pressure in cylinder 5 is maintained between 60 and 65 pounds per square inch, and if lever 18 engages contacts 27 and 28, pressure in cylinder 5 is maintained between 80 and 85 pounds per square inch. If lever 18 is moved into engagement with contacts 29 and 30, windings 8 of valves D and E are both energized directly and under these conditions valve E remains closed and the entire available pressure is supplied to cylinder 5.

I will assume that it is desirable to reduce the braking pressure from a high value such as 60 pounds per square inch, to a lower value such for example as 20 to 25 pounds per square inch. To do this, lever 18 is moved into engagement with contacts 21 and 22. Because of the high pressure existing in cylinder 5 circuit controllers K²⁰ and L²⁵ are both open so that the circuits for valves D and E are both open. Fluid pressure is therefore exhausted through valve E until the pressure in cylinder 5 is reduced below 25 pounds per square inch. Circuit controller L²⁵ thereupon closes, completing the circuit for valve E and preventing further reduction in cylinder 5. The

pressure is then maintained between 20 pounds and 25 pounds per square inch as already explained.

If the operator wishes to restore the braking bars to their non-braking positions, he moves lever 18 into engagement with contact 19. Current then flows from terminal B, through lever 18, contact 19, and winding 8 of valve F, to terminal C. Plunger 7 of valve F therefore moves downwardly and fluid pressure is admitted to the right-hand end of cylinder 5. The circuits for valves D and E are now open so valve D is closed and valve E is open to exhaust the left-hand end of cylinder 5 to atmosphere. Piston 6 therefore moves to the left and drives the braking bars to their non-braking positions. The lever 18 may then be returned to the position in which it is illustrated in the drawing wherein the circuits for all of the valves D, E and F are open.

I do not claim as my invention the combination of a plurality of pressure responsive devices subjected to the pressure in the operating cylinder and in turn actuating a plurality of circuit controllers for governing the valve which admits fluid pressure to said cylinder, such combination being the invention of John P. Coleman and disclosed and claimed by him in an application for Letters Patent of the United States, filed April 26, 1926, Serial No. 104,566, for railway braking apparatus.

Although I have herein shown and described only one form of railway braking apparatus embodying my invention, it is understood that various changes and modifications may be made therein within the scope of the appended claims without departing from the spirit and scope of my invention.

Having thus described my invention what I claim is:

1. Railway braking apparatus comprising a braking bar located in the trackway, a fluid pressure motor for operating said bar, a first valve for admitting fluid pressure to said motor, a second valve for exhausting pressure from said motor, and two circuit controllers both responsive to the pressure in said motor and each controlling one of said valves.

2. Railway braking apparatus comprising a braking bar located in the trackway, a fluid pressure motor for operating said bar, a first valve for admitting fluid pressure to said motor, a second valve for exhausting pressure from said motor, a first series of circuit controllers arranged to be successively operated as the pressure in said motor increases, a second series of circuit controllers arranged to be successively operated as the pressure in said motor increases, and manually operable means for controlling said first valve by any selected one of said first series of circuit controllers and

for simultaneously controlling said second valve by a corresponding circuit controller of said second series.

3. Railway braking apparatus comprising a braking bar located in the trackway, a fluid pressure motor for operating said bar, a first magnet valve for admitting fluid pressure to said motor, a second magnet valve for exhausting fluid pressure from said motor, two series of circuit controllers the circuit controllers of each series being successively operated as the pressure in said motor increases, and means for connecting said first valve in series with a selected circuit controller of one series and for simultaneously connecting said second valve in series with a corresponding circuit controller of the other series.

4. Railway braking apparatus comprising a braking bar located in the trackway, a fluid pressure motor for operating said bar, two circuit controllers responsive to the pressure in said motor and arranged to be operated at different values of said pressure, a first valve for admitting fluid pressure to said motor, a second valve for exhausting fluid pressure from said motor, and means for simultaneously controlling said first valve by one of said circuit controllers and said second valve by the other said circuit controllers.

5. Railway braking apparatus comprising a braking bar located in the trackway, a fluid pressure motor for operating said bar, two series of circuit controllers responsive to the pressure in said motor and the individual circuit controllers of each series being arranged to operate successively as the pressure in said motor increases, a first magnet valve arranged when energized to admit fluid pressure to said motor, a second magnet valve arranged when de-energized to connect said motor with atmosphere, and means for connecting any selected circuit controller of one series with said first valve, and for simultaneously connecting said second valve with a corresponding circuit controller of the other series.

6. Railway braking apparatus comprising a braking bar located in the trackway, a fluid pressure motor for operating said bar, two series of normally closed circuit controllers responsive to the pressure in said motor and the individual circuit controllers of each series being arranged to open successively as the pressure in said motor increases, a first magnet valve arranged when energized to admit fluid pressure to said motor, a second magnet valve arranged when de-energized to connect said motor with atmosphere, and means for connecting any selected circuit controller of one series with said first valve, and for simultaneously connecting said second valve with a corresponding circuit controller of the other series.

7. Railway braking apparatus comprising a braking bar located in the trackway, a fluid pressure motor for operating said bar, two normally closed circuit controllers responsive to the pressure in said motor and arranged to open at different values of said pressure, a normally closed magnet valve arranged when energized to admit fluid pressure to said motor, a normally open magnet valve arranged when energized to disconnect said motor from atmosphere, and means for connecting said circuit controllers in series with said two magnet valves respectively.
8. Railway braking apparatus comprising a braking bar located in the trackway, a fluid pressure motor for operating said bar, two normally closed circuit controllers responsive to the pressure in said motor and one arranged to open when such pressure exceeds one predetermined value and the other arranged to open when such pressure exceeds a higher predetermined value, means controlled by said one circuit controller for admitting fluid pressure to the motor, and means controlled by the other said circuit controller for exhausting fluid pressure from the motor.
9. Railway braking apparatus comprising a braking bar located in the trackway, a fluid pressure motor for operating said bar, a first series of circuit controllers arranged to be operated successively as the pressure in said motor increases, a second series of circuit controllers each of which is arranged to operate when the pressure in said motor exceeds a slightly higher value than that necessary to operate the corresponding circuit controller of the first series, a first magnet valve for admitting fluid pressure to said motor, a second magnet valve for exhausting fluid pressure from said motor, and means for controlling said first valve by any selected circuit controller of said first series and for simultaneously controlling said second valve by the corresponding circuit controller of the second series.
10. Railway braking apparatus comprising a braking bar located in the trackway, a cylinder containing a reciprocable piston operatively connected with said bar, a first magnet valve arranged when energized to supply fluid pressure to one end of said cylinder and when de-energized to connect such end of the cylinder with atmosphere, a second magnet valve arranged when energized to admit fluid pressure to the other end of said cylinder and when de-energized to interrupt such admission, a third magnet valve arranged when de-energized to connect such other end of the cylinder with atmosphere and when energized to interrupt such connection, a first series of normally closed circuit controllers responsive to the pressure in said other end of the cylinder and arranged to be successively opened as such pressure increases, a second series of normally closed circuit controllers also responsive to the pressure in said other end of the cylinder and arranged to be successively opened as such pressure increases, each circuit controller of said second series being arranged to open when the pressure in such other end of the cylinder exceeds by a slight amount the value necessary to operate the corresponding circuit controller of said first series, and a selector for at times supplying current to said first magnet valve and for at other times supplying current to said second magnet valve over a selected circuit controller of said first series and for simultaneously supplying current to said third magnet valve over the corresponding circuit controller of said second series.

In testimony whereof I affix my signature.

LLOYD V. LEWIS.
